INJECTION SYSTEM FOR ELECTRIC DEVICE
Hubert Leboutez, Paris, France, assignor to Compagnie
Generale de Telegraphie Sans Fil, Paris, France
Filed Dec. 7, 1959, Ser. No. 857,831
Claims priority, application France Dec. 24, 1958
4 Claims. (Cl. 176—5)

The present invention relates to devices in which the plasma, that is, an electrically neutral gas constituted by a mixture of ions and electrons, is compressed with a view to carry the same at a relatively high kinetic temperature that may eventually lead to a reaction of thermonuclear fusion.

More particular, the present invention relates to the type of devices having so-called magnetic mirrors, i.e., to the devices constituted generally by an evacuated vessel or enclosure having two distinct extremities in which is produced a longitudinal magnetic field intermediate these two extremities, this magnetic field being uniform except within the regions adjacent the extremities where the lines of force are compressed or constricted. This region of compressing or constriction of the magnetic field constitutes a magnetic mirror which reflects the charged particles moving in the direction toward the magnetic mirror regardless of the sign thereof. The totality of the lines of force of the longitudinal field together with the constrictions at the extremities thereof effectively define a so-called "magnetic bottle" which surrounds or envelops the plasma and which compresses the same while at the same time confining the plasma within a region of the space insulated from the walls of the vessel or enclosure.

In view of the inevitable losses of the particles across the walls or the extremities of the magnetic bottle as well as in view of the necessity to evacuate the "burnt-up" particles and to replace the same by fresh particles, it is necessary to inject periodically fresh plasma into the vessel in such a manner that the plasma is retained at the interior of the magnetic bottle.

Consequently, there arises the problem of a practical realization of an injection system in such a manner that the plasma may enter into the magnetic bottle at the moment of injection but that the bottle is closed as tightly as possible between injection periods.

There is known an injection system in the prior art under the designation of DCX (see "Project Sherwood," by A.S. Bishop, 1958, page 136), which system is based on the projection across the walls of the bottle of a beam of molecular ions having a high energy which dissociate themselves at least in part along an arc established at the interior of the bottle into atomic ions of which the mass is two times less. These ions turn about lines of force of the magnetic field of the bottle along trajectories which remain at the interior of the zone of confinement, whereas the molecular ions of double mass return toward the source.

One inconvenience and shortcoming of this prior art system is the fact that the arc within the zone of confinement determines a cold region with respect to the high temperatures under consideration, and the plasma as a result thereof is cooled off by the effect of this zone to such a point that the possibility of obtaining the desired high temperatures may be impaired.

Accordingly, it is a main object of the present invention to provide a new and improved injection system for the plasma which avoids the shortcomings and inadequacies of the prior art mentioned hereinabove.

Another object of the present invention resides in the provision of an injection system for plasma which does not result in any cooling of the plasma during injection.

Still another object of the present invention resides

2

in the provision of an injection system for plasma which is simple in construction, readily controllable, yet effective and reliable in operation.

A still further object of the present invention resides in the provision of an injection system for plasma normally confined within a magnetic field of bottle-shape configuration in which the bottle of the magnetic field is effectively opened only temporarily to admit fresh plasma.

These and other objects, features and advantages of the present invention will become more obvious from the following description when taken in connection with the accompanying drawing which shows, for purposes of illustration only, one embodiment in accordance with the present invention, and wherein:

FIGURE 1 is a longitudinal cross-sectional view of an injection system in accordance with the present invention;

FIGURE 2 is a diagram indicating the respective position of the control pulses along the time basis, and

FIGURES 3a to 3g illustrate a series of schematic views of the arrangement of FIGURE 1, illustrating the different stages during a cycle of operation thereof.

According to the present invention, the chamber for the production of high kinetic temperature is in communication with an injection chamber, the passage of particles from one chamber to the other chamber between injections being effectively prevented by a magnetic mirror having a controlled opening thereof at the moment of the injection and thereby operating as a so-called "magnetic shutter." Prior to opening of the magnetic shutter, the plasma is injected into the injection chamber where it is confined and compressed in a second magnetic bottle which is closed on one side thereof by the shutter in question and on the other by a movable magnetic mirror operating in the manner of a "magnetic piston" which pushes or displaces the plasma toward the shutter.

Referring now to the drawing, wherein like reference numerals are used throughout the various views to designate corresponding parts, and more particularly to FIGURE 1, which is a longitudinal cross-sectional view of an injection system according to the present invention, reference numeral 1 designates a cylindrical element, for example, of Pyrex in which are produced the high temperatures of the plasma. The necessary vacuum is continuously maintained within the cylinder 1 by means of the vacuum pump 2 which may be of any suitable construction. Several magnetic coils or windings are disposed about cylinder 1, namely as follows:

A first coil assembly 3 is provided which is intended to produce the magnetic field of correct form for confining and stabilizing the plasma within the cylinder 1. An auxiliary coil 4 is provided at the left end of the cylinder 1, as viewed in FIGURE 1, which is intended to produce a magnetic mirror within the region of the left end or extremity of the cylinder 1. A coil 5 is disposed essentially in the center portion of the cylinder 1 which is intended to produce a magnetic mirror within a region intermediate the two extremities of the cylinder 1. The space within cylinder 1 between the left end thereof and the region of the coil 5 constitutes the chamber for the production of the high temperatures. All of the coils described so far hereinabove are supplied continuously from suitable electric current sources, not illustrated in the drawing.

An auxiliary winding 6, wound in the opposite direction with respect to coil 5 is disposed along the inside of the latter. The auxiliary winding 6 is supplied from a controlled current source 7 which, when controlled by a control pulse, as will be explained more fully hereinafter, transmits to the winding 6 a current pulse of such intensity that the magnetic action of the winding 5 is momentarily annulled.

The portion of the cylinder 1 between the region of the

coil 5 and the right extremity of cylinder 1 constitutes the injection chamber. The injection chamber portion of cylinder 1 is surrounded by a coil assembly 8 analogous to that of the coil assembly 3, which is also supplied continuously from a suitable current source, not illustrated in the drawing, and which serves the purpose of creating the magnetic confining field within the injection chamber. An auxiliary winding 9 is disposed on the inside of the coil assembly 8 of which the turns are periodically connected to one side of shunt condensers 10, the other side of which are each connected to ground. The totality of coil portions 9 and condensers 10 in effect constitute a delay line having predetermined delay characteristics, as is well known in the art. Adjacent the winding 5, the delay line 9, 10 is terminated by a matched resistance or impedance 11. On the opposite end, the delay line 9, 10 is connected to a control current source 12 which, when controlled by a control pulse, as will be described more fully hereinafter, sends a current pulse along the delay line 9, 10.

An ion gun 13 and an electron gun 14 of conventional construction extend into the right extremity of the injection chamber. It is understood that the ion and electron guns, illustrated schematically by blocks 13 and 14, are, in fact, of any known structure which include all of the necessary electrodes, power supplies, and gas supply sources such as, for instance, deuterium for the ion gun. The ion gun 13 and the electron gun 14 as well as the necessary parts thereof thus constitute effectively the plasma injection means of the system. The control electrodes of the guns 13 and 14 are connected to the terminal *a* of a rotary distributor 15 of any known mechanical or preferably electronic construction, of which the terminals *b* and *c* are connected respectively to the sources 12 and 7. It is understood that the actual construction of the distributor 15 may be different from the symbolic illustration of FIGURE 1 and that its actual construction is preferably any known electronic arrangement. Reference numeral 16 designates a pulse source of any suitable construction which transmits or applies the control pulses through the intermediary of the distributor 15, at the proper timed moments, to the terminals *a*, *b* and *c*.

Operation

The operation of the system illustrated in FIGURE 1 will be better understood by reference to the diagram of FIGURE 2 and to the schematic illustrations of FIGURES 3a-3g.

The condition of the system prior to injection of the plasma is represented in FIGURE 3a. The coil 3 produces longitudinal magnetic lines of force 17, whereas the windings 4 and 5 produce respectively the constrictions 18 and 19 of the lines of force forming the so-called "magnetic mirrors." The totality of the lines of force 17, 18 and 19 form so-called "magnetic bottle." The winding 8 produces the lines of force 20 such that the totality of the lines of force 19, 20 forms within the injection chamber a magnetic bottle closed at 19 but open at the opposite end thereof.

At the moment t_a (FIGURE 2), the arm of the distributor 15 is effectively in contact with the terminal *a*, and a control pulse 21 is transmitted from the source 16 to the control electrodes of the guns 13 and 14. As a result thereof, the gun 13 injects into the injection chamber a cloud of ion gas, for example, deuterons, whereas the gun 14 injects an essentially equal quantity of free electrons. The injection may take place at a relatively high energy level, for example, of the order of 100 kev. The ions and electrons intermingle and form the plasma 22 (FIGURE 3b).

At the moment t_b , approximately at which terminates the pulse 21 (FIGURE 2), the arm of the distributor 15 passes over to the terminal *b*, and as a result thereof, a control pulse is transmitted to the source 12 which sends a pulse 23 (FIGURE 2) to the winding 9. At this moment (FIGURE 3c), the magnetic field within the

vicinity of the guns 13 and 14 is reinforced, whereby a constriction or narrowing 24 is effectively formed along the lines of force 20, and the plasma is enclosed within the magnetic bottle comprised between the constrictions 19 and 24.

The pulse 23 thereupon propagates along the delay line formed by elements 9 and 10 and therewith also displaces simultaneously the constriction 24. FIGURE 3d shows an intermediate position of the constriction 24 from which may be readily seen that the magnetic bottle defined by the constrictions 19 and 24 becomes shorter and shorter and that the constriction 24 in effect acts in the manner of a "magnetic piston," pushing the plasma 22 toward the chamber for the production of high temperatures and compressing the same within the magnetic bottle intermediate the constricted portions 19 and 24.

FIGURE 3e corresponds to the moment t_c at which the pulse 23 has arrived at the left end of the delay line 9, 10 and is absorbed by the resistance 11. Consequently, the pulse at t_c is illustrated in FIGURE 2 in dash lines and designated therein by reference numeral 23'. The plasma 22 is at the same time compressed to the maximum between the constrictions 19 and 24 and the latter constriction 24 is at that time in its end position.

At this moment, the arm of the distributor 15 passes over the terminal *c*. The source 16 thereupon transmits a control pulse to the current source 7 which, in turn, sends a pulse 25 (FIGURE 2) to the winding 6. The field of the coil 5 is thereby compensated so that the constricted portion 19 temporarily disappears (FIGURE 3f), the magnetic bottle of the chamber for the production of high temperatures is opened and the plasma 22 is injected therein. Thus, the system of elements 5, 6 and 7 operates in the manner of a "magnetic shutter" of which the release permits the momentary injection into the left chamber of the plasma previously compressed within the right chamber of FIGURE 1.

Once the pulse 25 is terminated, the constriction 19 reappears (FIGURE 3g) and the plasma is thereupon enclosed within the magnetic bottle of the chamber for the production of high temperatures comprised between the constrictions 18 and 19. The plasma, therefore, remains under the effect of compression of this bottle during a certain time during which the temperature thereof increases, and eventually may lead to a thermonuclear reaction. Thereafter, the burnt-up particles are evacuated by the pump 2, the system returns to the condition of FIGURE 3a, and the cycle recommences.

While I have shown and described one embodiment in accordance with the present invention, it is understood that the same is not limited thereto but is susceptible of many changes and modifications within the spirit and scope of the present invention and I therefore, do not wish to be limited to the specific details shown and described herein but intend to cover all such changes and modifications as are encompassed by the scope of the appended claims.

I claim:

1. In a plasma-confining device, an evacuated vessel comprising a high temperature production chamber and a plasma injection chamber, means for establishing in said high temperature production chamber a magnetic field having lines of force extending substantially along said chamber between both extremities thereof to effectively confine plasma particles to be injected therein, magnetic mirror means at both said extremities to prevent escapement of said particles from said chamber, said injection chamber being defined between one of said magnetic mirror means and one extremity of said vessel, means for injecting ions and electrons for forming plasma into said injection chamber, means effectively constituting magnetic piston means for compressing plasma and effectively pushing it towards said one magnetic mirror means, and means effectively constituting magnetic shutter means for momentarily canceling the effect of said one magnetic

mirror means after the compression of said plasma to thereby inject said compressed plasma into said high temperature production chamber.

2. A device as claimed in claim 1, wherein said magnetic shutter means includes a magnetic coil producing, upon energization thereof, a magnetic field opposite said one magnetic mirror field, and means including a pulse generator and connecting means from said generator to said coil for periodically sending an electric pulse through said coil.

3. A device as claimed in claim 1, further comprising means for establishing in said plasma injection chamber a magnetic field having lines of force extending substantially along said chamber between said one magnetic mirror means and said one extremity of said vessel, and wherein said magnetic piston means is formed by a delay line extending along said injection chamber, and means including a pulse generator and a connection from said pulse generator to the said delay line adjacent said one vessel extremity for periodically sending through said line an electric pulse propagating therealong towards said one magnetic mirror means and thereby effectively forming a magnetic mirror movable along said injection chamber.

4. A device as claimed in claim 1, further comprising timing means for controlling said ion and electron injecting means, said magnetic piston means and said mag-

netic shutter means to thereby produce a periodic sequence of operation consisting of initially injecting the ion and electron particles, then effecting plasma compression by said magnetic piston means, and finally operating 5 said magnetic shutter means.
